UNITED STATES PATENT OFFICE.

FRANK J. EBLE, OF ASTORIA, NEW YORK.

HANDBAG BABY-CARRIAGE.

1,361,698.

Specification of Letters Patent. Patented Dec. 7, 1920.

Application filed November 11, 1919. Serial No. 337,155.

To all whom it may concern:

Be it known that I, FRANK J. EBLE, a citizen of the United States, residing at Astoria, Long Island City, State of New York, have invented new and useful Improvements 5 in Handbag Baby-Carriages, of which the following is a specification.

This invention relates to improvements in baby carriages and the principal object of 10 the invention is to so construct a carriage that it may be folded into the shape of a hand satchel so that it may be easily transported when not in use.

Another object of the invention is to provide 15 a false bottom for the carriage which is connected with the main bottom by springs, affording easy riding of the carriage.

Still another object of the invention is to 20 provide foldable axles with means for pivoting them to one of the bottoms and also to provide a foldable top which may be detached from the carriage and placed within the body when the same assumes the form 25 of the satchel.

The invention also consists in certain other features of construction and in the combination and arrangement of the several parts, to be hereinafter fully described, 30 illustrated in the accompanying drawings and specifically pointed out in the appended claims.

In describing my invention in detail, reference will be had to the accompanying 35 drawings wherein like characters denote like or corresponding parts throughout the several views, and in which:—

Figure 1 is a view showing the device 40 folded in the form of a satchel.

Fig. 2 shows the device with the parts arranged to form the carriage.

Fig. 3 is a sectional view showing the parts of one side unfolded and the parts of the other side folded.

Fig. 4 is an enlarged fragmentary view 45 of one end of the bottom of the carriage showing the channel support of the axle.

Fig. 5 is a detail view of one part of one axle.

Figs. 6 and 7 are detail views of the foldable top.

In these views 1 indicates the main bottom to which the sides 2 and the ends 3 are hinged. The free parts of the sides are 55 curved so that when the said sides are in one position their free edges will come to-

gether as shown in Fig. 1, and when in the other position they will diverge from each other as shown in Fig. 2. The ends 3 have their free ends reduced so as to receive the curved parts of the sides, as shown in Fig. 1, and in order to fill the spaces between these reduced parts of the ends and the curved parts of the sides when in position shown in Fig. 2 I provide canvas or like material 4 which is connected to said sides and ends and is foldable so as to lie within the satchel when the parts assume the shape shown in Fig. 1. The free edges of the sides are provided with the handles 5 by which the satchel may be carried.

6 indicates a false bottom which is connected with the main bottom by the coiled springs 7 and the leaf springs 8. This false bottom carries a pair of channel-shaped members 9 which have their ends bent at right angles and extending around the side edges of the bottom as shown at 10. These channel members receive the sectional axles, each axle comprising the two parts 11 and 12. The inner ends of these two parts are pivoted to the channel member as shown at 13 and the outer ends are reduced, as at 14, to receive the angle shaped spindle member 15 which carries the spindle 16 for the wheel 17. The member 15 is pivoted to the reduced end 14 as at 18. In this way each part of the axle may be swung into or out of engagement with the channel member, as shown in Fig. 3 and the spindle member can be moved at right angles to each part of the axle so that the axles and wheels can be contained within the satchel. When the axle is swung into engagement with the channel member the spindle member will have one part thereof engage the part 10 of the channel member and thus the weight of the parts, when the same are arranged as a carriage will hold the axles in engagement with the channel members and the parts of the axle in extended position.

It will thus be seen that when the parts are arranged in the form of a carriage the axles and wheels are carried by the false bottom which is connected with the main bottom and the body of the carriage by the springs so that shocks and jars incident to the travel of the carriage along the road will be absorbed by said springs. By the shape of the side and end pieces and the canvas connecting the upper parts of the same together with the body of the carriage

is of outwardly flaring shape so that the infant may be easily placed in the carriage together with the pillows and covers.

When the carriage is not in use the parts 5 of the axles are turned upon their pivots as shown at the right of Fig. 3 and the ends and sides are turned so that these parts will assume the shape of a satchel. This will place the false bottom and the axles and 10 wheels within the satchel so that all the parts are hidden from view and the device will have the appearance of an ordinary satchel.

I also provide a foldable top 19 for the 15 carriage and a handle 20. The top is pivoted to the side pieces of the handle, as at 21, and the ends of these side pieces are forked, as at 22, with the forks made of 20 springy material so that they will grip and hold the studs 23 carried by the side pieces 25 of the carriage. The handle is made telescopic, as at 24, so that it can be folded together and placed within the satchel. The top 19 is also made so it can be folded and placed within the satchel when not in use. Said top may be adjusted on the handle and held in adjusted position by thumb nuts or the like.

It is thought from the foregoing description that the advantages and novel features 30 of my invention will be readily apparent.

I desire it to be understood that I may make changes in the construction and in the combination and arrangement of the several 35 parts, provided that such changes fall within the scope of the appended claims.

What I claim is:—

1. A device of the class described comprising a bottom, side and end pieces hinged 40 thereto, said pieces being of such form as to provide a satchel in one position thereof and a carriage body in the other position thereof, a false bottom of less dimensions than the main bottom, springs for supporting 45 the same from the main bottom, axle parts pivotally connected with the false

bottom and wheels carried by the said axle parts.

2. A device of the class described comprising a main bottom, side and end pieces 50 hinged thereto and of such form as to form a satchel in one position thereof and a carriage body in the other position, a false bottom, spring means connecting the same with the main bottom, channel members carried by the false bottom, axle parts pivotally connected with said channel members, spindle carrying members pivoted to said axle parts and wheels carried by said spindles. 55

3. A device of the class described comprising a main bottom, side and end pieces hinged thereto, said parts being of such form as to form a satchel in one position thereof and a carriage body in the other position 60 thereof, a false bottom, spring means connecting the same with the main bottom, foldable axle parts carried by said false bottom, wheels carried by said axle parts, a handle, means for detachably securing the same to the side pieces and a foldable top detachably connected with the handle. 65

4. A device of the class described comprising a main bottom, side and end pieces 70 hinged thereto and of such form as to form a satchel in one position thereof and a carriage body in the other position, a false bottom, spring means connecting the same with the main bottom, channel members carried 75 by the false bottom, axle parts pivotally connected with said channel members, spindle carrying members pivoted to said axle parts and wheels carried by said spindles, each of said spindle carrying members being 80 of angle shape with one portion extending upwardly along the side edge of the false bottom when the device is being used as a carriage. 85

In testimony whereof I affix my signature. 90

FRANK J. EBLE.
